Primary Examiner — Sandra Snapp

(57) **CLAIM**

We claim the ornamental design for the massager, as shown and described.

DESCRIPTION

FIG. 1 is a first perspective view of the massager of the present invention.

FIG. 2 is a second perspective view of the invention shown in FIG. 1.

FIG. 3 is a top view of the invention shown in FIG. 1.

FIG. 4 is a bottom view of the invention shown in FIG. 1.

FIG. 5 is a first side view of the invention shown in FIG. 1.

FIG. 6 is a second side view of the invention shown in FIG. 1.

FIG. 7 is a front view of the invention shown in FIG. 1; and,

FIG. 8 is a back view of the invention shown in FIG. 1.

The ornamental design which is claimed is shown in solid lines in the drawings.
